UNITED STATES PATENT OFFICE.

WILLIAM A. STOLLEY, OF DOWAGIAC, MICHIGAN, ASSIGNOR, BY MESNE ASSIGNMENTS,
TO JAMES HEDDON'S SONS, OF DOWAGIAC, MICHIGAN, A CORPORATION OF
MICHIGAN.

DESIGN FOR ARTIFICIAL BAIT.

52,925.

Specification for Design.

Patented Jan. 28, 1919.

Application filed July 20, 1915. Serial No. 41,009. Term of patent 14 years.

To all whom it may concern:

Be it known that I, WILLIAM A. STOLLEY, a citizen of the United States, residing at Dowagiac, in the county of Cass and State of Michigan, have invented a new and original and ornamental Design for Artificial Bait, of which the following is a specification, reference being had to the accompanying drawing, forming a part thereof.

Figures 1 and 2 are respectively a side elevation and top plan of the artificial bait showing my new design.

I claim:

The ornamental design for artificial bait as shown.

WILLIAM A. STOLLEY.

Copies of this patent may be obtained for five cents each, by addressing the "Commissioner of Patents, Washington, D. C."
